United States Patent Office

Des. 211,672
Patented July 9, 1968

211,672

FACIAL TISSUE

Archie G. Drummond, Jr., Wantagh, N.Y., assignor to
The Procter & Gamble Company, Cincinnati, Ohio, a
corporation of Ohio

Filed May 10, 1967, Ser. No. 7,060

Term of patent 14 years

(Cl. D59—2)

FIG.1

FIG. 2

FIG. 1 is a plan view of a full width of facial tissue showing my new design, the design unit being shown within the broken lines, the unit repeat being as indicated in the extensions beyond the broken lines.

FIG. 2 is a fragmentary plan view thereof on an enlarged scale.

I claim:

The ornamental design for facial tissue, as shown and described.
